UNITED STATES PATENT OFFICE

ROBERT M. BURNS, OF KENILWORTH, ILLINOIS, ASSIGNOR TO CHAMBERLIN METAL WEATHERSTRIP COMPANY, OF DETROIT, MICHIGAN, A CORPORATION OF MICHIGAN

WEATHER STRIP

Application filed June 22, 1929. Serial No. 372,959.

This invention relates to weatherstrips and the object of the invention is to provide a weatherstrip for a swinging wood casement or door and arranged to seal the outer face 5 of the door or casement as well as the edge thereof.

A further object of the invention is to provide a spring metal weather strip adapted to seal two faces of the closure member, one 10 seal being a sliding contact and the other seal being a pressure contact.

A further object of the invention is to provide a spring metal weatherstrip bent at a right angle and having two inwardly extending 15 spring metal flanges adapted to be engaged by the edge and face respectively of the closure member.

These objects and the several novel features of the invention are hereinafter more 20 fully described and claimed and the preferred form of construction by which these objects are attained is shown in the accompanying drawings in which—

Fig. 1 is an elevation of a swinging casement with which the weatherstrip is used.

Fig. 2 is an enlarged section through the window frame showing the weatherstrip mounted therein.

Fig. 3 is a similar section showing the swinging casement in relation to the weatherstrip and window frame.

Fig. 4 is a perspective view of a portion of the weatherstrip.

Fig. 5 is a section showing an alternative form of the weatherstrip in relation to the swinging casement and frame.

Fig. 6 is a section showing another alternative form of the weatherstrip in relation to the window frame.

Fig. 7 is a section showing the swinging casement in operative relation with the weatherstrip and window frame shown in Fig. 6.

Fig. 8 is a section through another alternative form of weatherstrip as utilized with an alternative form of window frame.

Fig. 9 is a similar view showing the closure member in relative relation therewith.

Fig. 10 is a section showing another alternative form of weatherstrip.

The principle of operation throughout the various alternative forms of weatherstrip is the same in that the weatherstrips each seal the edge and face of the swinging closure member. In Figs. 2, 3 and 4 the weatherstrip comprises a flat spring metal base portion 1 having a flange 2 extending therefrom at a right angle and this flange 2 engages against the shoulder 3 formed in the window frame. At the outer edge of the base portion 1 is 55 return bent upon itself to form a portion through which securing nails 4 may be driven and this return bent portion terminates in an angularly extending spring metal flange 5 which may be provided with a hemmed termi- 60 65

The flange 2 is provided with a bead 7 rolled therein from which the flange 8 extends at an angle toward the flange 5 and this flange 8 may be provided with a hemmed or return bent terminal edge 9 if desired. As the swinging casement is swung to the closed position, the edge 10 thereof rides in contact with the flange 5 of the weatherstrip thus depressing this flange and sealing the casement at the edge while the face 11 of the casement engages the spring metal flange 8 and compresses it as shown in Fig. 3 thus also sealing the face of the casing. By this arrangement the casement is sealed at two 70 75 80 points against the weather.

It will be noted from Fig. 3 that the bead 7 extends to the outside of the flange 2. In Fig. 5 an alternative form is shown in which a bead 12 is formed in the metal on the inside 85 of the flange 2 and a flange 13 is provided extending upwardly therefrom into contact with the face of the casing. In this view it will be noted that the face of the casing contacts the bead 12 as well as the spring metal 90 flange 13 and thus the face of the casement is sealed at two points.

An alternative form of the weatherstrip is shown in Figs. 6 and 7 in which the flange 2 is provided with an enlarged bead 14 rolled 95 therein and this bead is provided with an angularly extending spring metal flange 15 which extends into contact with the face 16 of the window frame.

When the casement is swung into the frame 100

it depresses the spring metal flange 5 and the face of the casement engages the bead 14 which is sufficiently large as to be somewhat yieldable so that the casement is sealed at 5 two points as shown in Fig. 7. With this form it is impossible for a driving rain to work in between the weather strip and the window frame due to the flange 15 which contacts the window frame and at the same time 10 the bead 14 seals the casement and prevents leakage between the casement and the bead 14 while the casement is also additionally sealed by the spring metal flange 5.

As shown in Figs. 8 and 9 windows and 15 frames are sometimes made with offset shoulders which inter-engage as shown in Fig. 9 when the casement is swung into closed position in the frame. For this construction a weatherstrip is provided as shown in Fig. 20 8 having a base portion 1 and return bent flange 5 and the securing nails 4 and this base portion 1 is provided with a flange 17 engaging against the face of the window frame 18 and provided with a return bent portion 25 19 through which additional securing nails 20 are driven into the window frame 18. The return bent portion 19 extends outwardly and is provided with a bead 21 rolled in the outer edge thereof from which 30 a spring metal flange 22 extends, as shown in Fig. 8. This bead 21 and flange 22 are similar to the bead 12 and flange 13 shown in Fig. 5.

When the casement 23 is swung to the 35 closed position, as shown in Fig. 9, the edge of the casement compresses the flange 5 while the face 24 of the casement compresses the flange 22 and engages the bead 21 thus sealing the casement at two points on its face 40 and at a single point on its edge. If desired the bead 21 and flange 22 may be replaced by the bead 7 and the flange 8 shown in Figs. 2, 3 and 4. In this form the weatherstrip is substantially T shaped and entirely covers 45 the joint between the casement and frame and prevents leakage through the space between the casing and frame.

In Fig. 10 an alternative form of the weatherstrip is shown in which the base member 50 1 is provided with a return bent flange 25 and the spring metal flange 5 is a separate piece and is slipped beneath the return bent flange 25 and the nails 4 are driven through the return bent flange 25 and spring metal flange 55 5 to secure the device to the window frame. In all other respects this form is the same as that shown in Fig. 2.

From the foregoing description it becomes 60 evident that the device is very simple and efficient in operation, will provide a double seal for hinged casement and doors, will provide a resilient stop for the casement or door and provides a device which accomplishes the objects described.

Having thus fully described my inven-

tion, its utility and mode of operation, what I claim and desire to secure by Letters Patent of the United States is—

1. In a weatherstrip, a base member 70 formed of spring metal and having a flange extending at a right angle thereto, a bead rolled into the outer edge of the said flange and having an integral spring metal flange extending toward the base member, the edge of the base member opposite the right angle flange being return bent to provide a spring metal flange extending at an angle toward the right angle flange, the two spring metal flanges extending toward each other normally at an angle greater than a right angle 75 with the free edges thereof in adjacent relation.

2. In a weatherstrip, a spring metal strip 80 bent to the form of a right angle in cross section, the outer edges of the strip being return bent into the angle formed by the sides of the strip, and normally lying at an angle greater than a right angle one to the other with the free edges in adjacent relation.

3. In a weather strip for introduction 85 between a frame and a hinged sash, said frame having a surface parallel with the peripheral edge of the sash and a surface parallel with the side face of the sash, a spring metal strip 90 having a base consisting of a portion attachable to the frame and fitting each of the said surfaces thereof, the opposite edges of the strip being return-bent toward the respective base portions and normally lying at an angle thereto with the free edges in adjacent spaced relation providing respectively for sliding contact with the respective peripheral edge and side face of the sash.

In testimony whereof I sign this specification.

ROBERT M. BURNS.
